ARRANGEMENT FOR VALVE TRANSMITTERS CONNECTED WITH A LOAD-EQUALIZING
TUBE

Application filed October 12, 1928, Serial No. 312,074, and in Germany October 17, 1927.

It is known in the prior art to provide valve transmitters whose working potential is supplied from a network, with load-compensating circuit means. The purpose of 5 the latter is to cause the potential source to operate upon a separate circuit during the spacing periods to prevent load fluctuations of the supply when signalling. For it will be understood that such variations of the 10 load are liable to occasion overvoltages, and this might endanger the operation of the transmitter equipment, not to mention this further circumstance that the working potential variations associated with such load 15 fluctuations often affect the frequency of the transmitter wave. Such frequency alterations will arise when the transmitter valve connected with the supply line is operated in what is known as a self-excitation scheme. 20 The load compensating circuits customarily provided in practice to preclude load fluctuations consist usually of one or more discharge tubes which are connected in parallel with the same network, and whose internal 25 resistance is controlled in dependence upon the keying in such a way that during the keying intermissions or spaces the decrease in the load of the network due to the interruption of the transmitter wave is compensated 30 by an increase in the load due to the load-compensator tube.

According to the present invention, the control of the load-compensator tube is to be effected automatically by the variation of 35 the grid direct current in the transmitter tube. If the said load-compensator tube consists of a triode, the controlling action is produced by varying the grid biasing potential of this load-compensating tube in 40 accordance with the variations in the direct current in the grid circuit of the transmitter valve. Proper control of the load on the source by the variations in the biasing potential results from the fact that the grid of 45 the load-compensating tube is given a more negative biasing potential when the transmitter valve is oscillating, and that the said bias is less negative or more positive whenever the oscillations cease.

50 One embodiment of the basic idea of the

invention is illustrated in the accompanying drawing. Referring to the latter, S is the transmitter valve in what is known as the three-point connection scheme, B the load-compensator tube. These two tubes are connected with the supply source network terminals H1 H2. Keying is effected by the aid of key T which interrupts the supply line to the transmitter tube S. The 55 load-compensating tube B is suitably united with the supply network by way of a resistance R. The grid of the load-compensating tube is connected with a resistance R_g which is included in the grid circuit of the transmitter valve. As can be seen readily from the diagram, a voltage drop will occur across the resistance R_g when T is closed and tube S and associated circuits are in the state of oscillation, and as a result a 60 negative biasing potential is imparted to the grid of the load-compensating tube B, with the consequence that the internal resistance of this tube becomes very high, whereas with opened key the voltage drop across resistance R_g and thus also the biasing potential at the load-compensating tube B disappear. By choosing suitable dimensions 65 for the tubes and the resistance it is possible to create conditions so that the load on the supply network remains unvaried 70 whether the transmitter is working or whether spacing occurs. In order that the radio frequency currents in the grid circuit may not cause any additional control 75 of the load-compensating tube, a condenser K is connected in parallel relation with resistance R_g for the object of creating a short-circuit for the radio frequency currents. The arrangement here disclosed has proved 80 satisfactory and is particularly valuable for 85 short-wave transmitters.

I claim:

1. In an oscillation system, an electron discharge tube having an input circuit and an output circuit, a power supply system for supplying energy to said tube, a second electron discharge tube having an input circuit and an output circuit said second mentioned tube being also connected to said power supply system and means common to 90

- both said input circuits for affecting the conductivity of said second mentioned tube in accordance with conditions in said first mentioned tube.
5. 2. In a system of the kind described, an oscillation generator comprising a space discharge device having input and output circuits, a power supply circuit for said space discharge device, a load compensator means, 10 comprising a second space discharge device having input and output circuits, and means common to said mentioned input circuits for affecting said second named space discharge device in opposite sense to conditions 15 in said first mentioned electron discharge device.
3. In an oscillation system an electron discharge device having an input circuit and an output circuit, a power supply system 20 for supplying energy to said device, a variable loading device shunted across said power supply system and means in said input circuit for controlling said variable loading device in accordance with the load placed upon said power supply system by 25 said electron discharge device in opposite senses whereby the total load on said system remains constant.
4. In a signal transmission system, means 30 for generating high frequency oscillations comprising an electron discharge device having an input circuit and an output circuit, a resistance in said input circuit, a power supply system for said space discharge device, a load compensator means comprising 35 a second electron discharge device having its anode and cathode circuit connected across said power supply system and its grid and cathode circuit connected across 40 said resistance, signal modulating means associated with said oscillation generator and means controlled thereby for affecting the conductivity of said second electron discharge device.
45. 5. In combination, an electron discharge device having high frequency input and output circuits, a resistance in series with the grid of said device, a condenser across said resistance for preventing the flow of high 50 frequency currents in said resistance, a source of potential connected to other electrodes of said device, a vacuum tube connected across said source, and means connecting said resistance to said vacuum tube whereby the 55 conductivity of said tube is varied in accordance with the unidirectional potential difference across said resistance.
6. In apparatus of the character described, 60 the combination of an electron discharge device having an anode a cathode and a grid, said device having in addition high frequency input and output circuits, a resistance in series with the grid of said device, a relatively large capacity condenser shunting said 65 resistance, a source of potential for supply-
- ing anode potential to the anode of said device, a tube having an anode a cathode and a grid connected across said source, said last mentioned grid being connected to said resistance whereby the conductivity of said tube is varied in accordance with the potential difference across said resistance thereby maintaining the anode potential applied to said electron discharge device substantially constant despite variations in high frequency load thereon. 70
7. The combination in a signal system of an electron discharge device having an anode, a cathode, and an output circuit associated with said anode, means for producing oscillations on the grid of said discharge device in accordance with desired signals whereby said oscillations are supplied to said output circuit, a source of electromotive force connected between said anode and cathode, the magnitude of oscillations supplied to said load circuit being dependent upon the electromotive force supplied to said anode, a second electron discharge device having an anode and cathode connected in 80 shunt with the anode and cathode of said first device and arranged normally to draw appreciable current from said source, and means responsive to oscillations on the grid of the first device for alternately transferring a portion of the load on said source from one of said devices to the other, thereby to prevent variations of potential in said source due to changes in magnitude of load 85 thereon. 90
8. In a signalling system, an electron discharge device having input and output electrodes and input and output circuits connected therewith, means for connecting the output electrode of said discharge device to a source of energizing current including a key, and means for maintaining a constant load on said source irrespective of the conductivity of said tube as determined by the position of said key comprising, a second 95 discharge device having its anode to cathode impedance connected in parallel with said source, said second discharge device having a control electrode, and means connected with said control electrode and with one of said 100 circuits to apply energy from one of said circuits to said control electrode, the amount of which is determined by the position of said key. 105
